ELECTRIC CONTACTOR AND ARC
EXTINGUISHER THEREFORLloyd Russell Ranson, Charlotte, N. C., assignor
to The Clark Controller Company, Cleveland,
Ohio, a corporation of Ohio

Application February 19, 1946, Serial No. 648,776

2 Claims. (Cl. 200—147)

1

This invention relates to electric contactors of the class having contacts for making and breaking electric circuits, at such potential and amperage that when the circuit is broken at the contacts a persisting arc tends to form thereat; but having magnetic means to quickly rupture and extinguish the arc.

In prior contactors of this general class, the magnetic arc extinguishing means or "magnetic arc blow-out" arrangement comprises some means to produce a magnetic field disposed adjacent to the arc and directionally related to the direction of the current in the arc so that the arc reacts on the magnetism of the field and is rapidly propelled across it by the well recognized motor principle, and is thereby quickly elongated and ruptured.

In the contactor of the present invention the reaction between magnetism and current generally, is applied in an improved construction and utilized in an improved manner to accomplish a number of useful effects which are believed to be novel in this art.

Generally speaking, the contactor is constructed so that when it breaks the main circuit which it controls, the arc produced at the break is subjected to two opposing magnetically produced forces, acting on the opposite sides of the arc, and squeezing it into a thin planar zone; and it is then ruptured by magnetic action; whereby arc flame is suppressed, and the arc readily and abruptly extinguished, and destructive contact of the arc with laterally adjacent parts is reduced or eliminated.

Furthermore, the contactor has a double-break contact arrangement comprising two sets of contacts, one of the contacts of each set being supported on a movable electrically conducting bridging construction, and magnetic forces are exerted on the bridging construction, tending to move and position it in a manner to cause the breaks at both contact sets to occur simultaneously, and to cause the wear or burning away of the two sets of contacts to be continuously equalized, throughout the life of the contacts.

It is among the objects of the invention to provide in an electric contactor:

A magnetic arc extinguisher having an improved construction and mode of operation;

An improved magnetic arc extinguishing arrangement operating in a manner to squeeze the arc into a thin planar zone, concurrently with rupturing the arc;

A magnetic arc extinguisher operating in an

2

improved manner to suppress or reduce arc flame;

Double break contacts having a construction and mode of operation, utilizing the reaction of current and magnetism, to cause the wearing or burning away of the contacts at the two breaks, to be continuously equalized so that over a long period of use the separation of the contacts at both breaks is maintained equal, and both breaks occur simultaneously, and the arc is divided equally between them.

Generally, it is an object of the invention to provide an electric contactor of the magnetic arc extinguishing class having an improved construction and mode of operation.

Other objects will become apparent to those skilled in the art to which the invention appertains, from a reading of the following description which fully discloses the invention, taken in connection with the accompanying drawing, in which:

Fig. 1 is a side elevational view of a contactor embodying the invention; with parts broken away and parts in section;

Fig. 2 is a front elevational view of the contactor of Fig. 1;

Fig. 3 is a top plan view of the contactor of Fig. 1;

Fig. 4 is a fragmentary side elevational view showing in elevation parts that are shown in section or broken away in Fig. 1;

Fig. 5 is a sectional view from the staggered plane 5 of Fig. 1 with parts omitted;

Fig. 6 is a sectional view from the plane 6 of Fig. 1 with parts omitted;

Fig. 7 is a sectional view from the plane 7 of Fig. 1 with parts omitted;

Fig. 8 is a sectional view from the plane 8 of Fig. 1 with parts omitted;

Fig. 9 is a sectional view from the plane 9 of Fig. 2 with parts omitted;

Fig. 10 is a fragmentary view similar to a part of Fig. 1 but with operative parts in different positions;

Fig. 11 is a top plan view showing separately the contacts of the other figures;

Fig. 12 is a diagrammatic view illustrating an operative feature of the contactor of the other figures.

The embodiment of the invention illustrated in the drawing as will appear from an inspection of the various figures particularly Figs. 1 to 4, 9, 10, and 11 comprises a pair of stationary contacts 1 and 2; a bridging element 3 comprising contact portions or contacts 4 and 5 thereon,

constituting movable contacts movable toward and from the stationary contacts 1 and 2 to engage and disengage them; and a magnetic arm 6 upon which the movable contacts are supported.

An electromagnet is provided for operating the arm 6 and comprises a steel element 7 bolted to an insulating panel 8 (constituting a main base upon which the parts of the contactor generally are mounted). The element 7 has a groove 9 therein. A horizontally extending steel piece 10 is seated at one end in the groove 9, and a bolt 11 projected through the panel 8 and through the steel piece 7 and screwed into the steel piece 10 mounts these pieces together, and upon the panel. An operating winding 12 surrounds a steel core 13 riveted as at 13A to the steel piece 7 at one end, and at the other end having a magnetic pole face 14. The arm 6 has legs 15-15 straddling the steel piece 10 and pivoted upon the latter by a pivot pin 16, the axis of the pivot being to the left (as viewed in Fig. 1) of the center of gravity of the arm 6 whereby the arm moves by gravity to the open-contact position illustrated; and its open contact position is adjustable by means of a stud 17 screwed vertically through the steel piece 10 and engaging a shoulder 18 on the arm 6. The arm 6 has a pole face 19 opposite the pole face 14 of the magnet, providing a working air gap 20, therebetween.

Upon energizing the winding 12, magnetism in the working air gap 20 rocks the arm 6 counter-clockwise as viewed in Fig. 1 to engage the contacts 1-4 and 2-5 and upon de-energizing it the arm 6 returns to its said normal position.

The stationary contacts 1 and 2 are detachably and renewably secured upon the ends of posts 21 and 22, preferably parallel and transversely spaced apart; the post 21 being mounted upon the panel 8 by a stud 23 and nut 24, and the stud 23 extending beyond the nut 24 and having another nut 25 thereon, by which an electric circuit to be controlled may be connected to the stud 23 and therefore to the contact 1.

The post 22 is mounted upon the panel 8 by a bolt 26. Electric circuit connection to the post 22 and therefore to the contact 2 is made through an arc blow-out magnetic winding 27 to be more fully described, one end of the winding being connected to the post 22 by a bolt 28, and the other end of the winding being connected to a bolt 29 passing through the panel 8 and having a clamping nut 30 thereon, and the bolt extending beyond the nut 30 and having another nut 31 thereon for making electrical connection to the bolt.

In the particular embodiment illustrated in the drawing, the two movable contacts 4 and 5 are each a part of and integral with a one piece bridging element 3, the movable contacts 4 and 5 thus constituting portions of the one piece bridging element; but it will be understood that the contacts 4 and 5 can be separately made and attached to a bridging element or bridging construction of other forms.

The bridging element 3 with its movable contacts 4 and 5 is mounted loosely on the arm 6 in a manner to maintain the contacts 4 and 5 in alignment with and confronting respectively the stationary contacts 1 and 2, but permitting what may be called generally a pivoting movement around a generally vertical axis between the contacts 4 and 5; and while this pivotal movement may be variously provided for, that provided in the particular construction illustrated is as follows.

A contact carrier 32 formed by bending a strip of metal into generally U-form has one leg 33, the upper leg as viewed in Figs. 1 and 10, attached by a screw 34 to the upper end of the arm 6; the closed end 35 of the U extends over the inner part of the bridging element 3 intermediate its ends; and the lower leg 36 of the carrier, being substantially parallel to the leg 33, is secured to the arm 6 by a bolt 37. On its upper side, the bridging element 3 has a notch 38 therein, Figs. 1, 7, 9, and 10, upwardly open, and its sides embrace the leg 33 of the carrier with clearance. A protuberance 39 is provided on the back side of the bridging element 3 substantially at its middle, and a protuberance 40 is provided on the arm 6, and a compression spring 41 is telescoped over the protuberances at its ends, and, in the open contact position, resiliently holds the bridging element 3 against the closed end 35 of the carrier.

As shown in Fig. 1, in the contact open position, the spring 41 has an angular or upward component of thrust on the bridging element 3, which, each time that the arm 6 moves to open contact position, pushes the notch 38 of the bridging element into the corner between the leg 33 and the closed end 35 of the carrier, which repeatedly positions or aligns the contacts 4 and 5 with the stationary contacts 1 and 2. The bridging element 3, however, is at all times free to rock about the closed end 35 of the carrier in a manner and for a purpose to be more fully described, and reference may be had to Fig. 8 wherein a normal position for the bridging element 3 is shown in solid line, and wherein at 3A and 3B, in broken line, it is shown in pivotally rocked positions.

In the operation of that part of the contactor thus far described, when the operating magnet 12 has moved the arm 6 counterclockwise as viewed in Fig. 1, the contact carrier 32 and the bridging element 3 and its contacts 4 and 5 move in unison with the arm through the first part of the movement, and the contacts 4 and 5 become engaged respectively with the stationary contacts 1 and 2. Thereafter the arm 6 continues to move until the air gap 20 of the operating magnet is completely closed, and during this latter part of the movement, the contacts 4 and 5 are stopped by their engagement with the stationary contacts 1 and 2 and the contact carrier 32 goes on moving and finally reaches the position illustrated in Fig. 10, the closed end 35 of the carrier leaving the bridging element 3, and the spring 41 being put under more compression and holding the contacts engaged. When the arm 6 returns to the open contact position, the closed end 35 of the carrier picks up the bridging element and moves the movable contacts back out of engagement with the stationary contacts 1 and 2.

When the contacts are in this manner closed or engaged, current in the circuit to be controlled by the contactor may be considered as flowing in at the stud 23, through the post 21, through the engaged contacts 1 and 4, thence transversely through the bridging element 3, through the engaged contacts 5 and 2, through the post 22, or a part of it, through the said blow-out winding 27, and out at the stud 29.

When the contact engagement is broken at the contacts 1-4 and 2-5, arcs will tend to be drawn at both sets of contacts.

In the absence of other provisions, it is inevitable that one set of contacts 1-4 and 2-5 would open before the other set, and draw one arc

earlier than the other, and burn or wear away one set of contacts more than the other; and the two sets of contacts would not continue to open simultaneously; and this condition would be aggravated by successive operations; so that after a short period of use the current would always be broken at one set of contacts only, with an attending destructive arc, difficult to extinguish.

By the provision of the construction illustrated and above described including the free pivotal movement of the bridging element 3, this disadvantage and defect is eliminated by the utilization of the reaction between current and magnetism which will now be described in connection with the theoretical diagrammatic figure, Fig. 12.

At 42 and 43 are represented conductors bridged at their lower ends as viewed in the drawing by a bridging conductor 44 making contact with the conductors 42 and 43, at 45 and 46 respectively.

The conductor 43 is shown shorter than the conductor 42, so that the conductor 44 makes an acute angle with the conductor 42, and an obtuse angle with the conductor 43.

Electric current may be considered as flowing in the direction of the arrow 47 through the conductor 42 and turning at an acute angle into the conductor 44, and flowing therethrough, and turning at an obtuse angle into the conductor 43, and flowing therethrough and out at the direction of the arrow 48.

This flowing current produces a magnetic field around the three conductors, the lines of force of the field as viewed from above being indicated by the lines 49. When the current makes an acute angle turn at the contact 45, the lines of force are crowded together as at 50; and when the current turns the obtuse angle at the contact 46, the lines of force are also crowded together as at 51, but less than at 50. Where the lines of force are crowded together as at 50 and 51 they repel each other in the effort of the field to straighten out, and this repulsion force is communicated to the conductor 44 and tends to move it and break the circuit at the contacts 45 and 46.

However, due to the greater crowding together of the lines of force at 50 than at 51, this repulsion on the conductor 44 at the gap 45 is greater than at the gap 46; and if the conductor 44 were free to move, it would break contact at 45 earlier than at 46.

By comparing Fig. 12 with Fig. 11, it will be observed that in Fig. 11 the conditions of Fig. 12 are generally present. Current flowing along the post 21 and through the engaged contacts turns a right angle on flowing into the bridging element 3, and turns another right angle flowing from the bridging element 3 through the contacts 5 and 2 into the post 22, so that when current is flowing, both ends of the bridging element 3 are subjected to forces in the direction to open the contacts.

In going from Fig. 10 to Fig. 1, the contacts may be said to be opened by engagement of the carrier closed end 35 with the middle of the bridging element 3, but the bridging element and its two contacts 4 and 5 are, by the construction described, free to pivot on the carrier portion 35 as shown in Fig. 8. Therefore if at the moment opening of the contacts starts, the direction of the current in the bridging element 3 between the contacts 4 and 5 is at right angles to the direction of current in the post 21 and con-

tact 1, and at right angles to the direction of the current in the contact 2 and post 22, the two propulsion forces on the contacts 4 and 5 will be equal and both sets of contacts will open simultaneously. If however, due to any cause whatever, such as inaccuracies in the original construction, or microscopic amount of wear at one set of contacts greater than at the other, the angular change of direction of the flowing current at the two sets of contacts should be unequal angles, the set of contacts at which the directional angle of the current is an acute angle will be opened first; and after a few operations the right angle condition of both sets of contacts will be established or restored, and thereafter maintained.

In view of the foregoing it will now be clear that this inherent and continuous equalizing action, causing both sets of contacts to break simultaneously and wear away equally and therefore draw equal arcs therebetween, results from giving the bridging element 3 and its contacts 4 and 5 the said pivotal movement intermediately thereof, and from utilizing the repulsion forces produced on the bridging element by the magnetism produced by the flowing current.

The arcs thus continuously equalized, are extinguished by arc extinguishing parts, proper, of the structure, and these comprise a magnetic circuit energized by the blow-out winding 27, and a pair of arc chutes, one for each set of contacts. The blow-out winding 27 is wound on an insulating spool 52, and while the winding 27 may be wound from round wire the one shown in the drawing is made from an edgewise wound strip of conductor such as copper. The insulating spool 52 is telescoped over a magnetic core 53. A magnetic yoke 54 is provided, generally of U-form, the closed end 55 of the U lying upon the panel 8 and the legs 56 and 57 of the U extending forwardly substantially parallel to the core 53, a bolt 58 passing through the closed end 55 of the yoke and into the core 53, mounting these elements on the panel 8.

Magnetic side plates 59 and 60 are pivotally connected to the legs 56 and 57 of the yoke by pivot bolts 61 and 62. A core extension 63 of magnetic material has an inner end surface 64 abutting upon the end of the core 53, and extends forwardly therefrom with its lower edge 65 above the contacts, see Fig. 1, and intermediately between them. The side plates 59 and 60, it is to be particularly noted, have magnetic protuberances 66 and 67 projecting inwardly from the side plates toward the core extension 63, their inner ends as shown in Figs. 5 and 6 overlapping a part of the contacts thereunder, and as shown in Figs. 1 and 9 for the protuberance 67 in dotted line, being approximately above the arc space between the contacts.

Referring to Fig. 5, and bearing in mind the direction of the winding 27, Figs. 1 and 11, and that the current (Fig. 11) flows in at the stud 23, through the post 21, through the contacts 1-4 and 5-2, and through the post 22 and through the winding 27 and out at the stud 29, the flux produced by the blowout winding 27 may be considered as flowing from the core 53 into the yoke 54 and there dividing, part flowing through the yoke leg 56, the side plate 59, the protuberance 66, across the space between the protuberance and the core extension 63, into this extension, and back to the core 53; and the other half flowing similarly through the leg 57, side plate 60, pro-

tuberance 61 and to the core extension 63 and back to the core 53.

The protuberances 66 and 67 may be formed separately and secured to the side plates as by welding. At their inner ends they are of smaller cross section than the side surfaces of the core extension 63. The magnetic flux will therefore be concentrated and of high density as it leaves the protuberances, and will spread out and be of low density as it enters the core extension 63, and is thus a tapering magnetic field.

The magnetic parts adjacent the contacts are covered with refractory material providing an arc chute for each set of contacts, and the parts of the magnetic circuit and of said arc chutes are all assembled rigidly together with the side plates 59 and 60. The said arc chutes and the refractory material thereof may if preferred be molded in one piece but in the construction illustrated, they are made from several pieces bolted together as follows. A side plate of refractory material 68 lines the inner face of the magnetic side plate 59 and covers, as at 69, the protuberance 66. A similar side plate 70 lines the inner side of the magnetic side plate 60 and covers the protuberance 67. These refractory side plates as shown for the side plate 70, Figs. 1 and 9, see also Fig. 6, extend downwardly below the contacts and forwardly and rearwardly thereof.

Inner refractory plates 71 and 72 are provided on opposite sides of the core extension 63 and overlap its lower edge 65 as shown at 73, Figs. 1 and 6.

Tubular refractory elements 74 and 75 are disposed respectively between the refractory plates 78 and 71, and 72 and 70, and a bolt 76 is projected through these parts and also through the core extension 63, and clamps these parts rigidly together. Refractory barriers 77 and 78 are provided having, at their upper ends, forwardly curving portions 79 and 80, and downwardly extending barrier portions 81 and 82 disposed as shown in Fig. 1 behind the contacting portion of the contacts 1 and 2, see also Figs. 6 and 9. Bolts 83 and 84, Figs. 1, 5, and 9, are projected through the side plates 59 and 60, the refractory plates 68-70, barriers 77-78, refractory plates 71 and 72, and through the core extension 63 and clamp these parts together rigidly.

The said pivot axis of the side plates 59 and 60 provided by the pivots 51 and 52, is above the axis of the main blow-out core 53, and upon this pivot axis the entire structure described and connected to the side plates, may be hinging or pivotally moved around upwardly to give access to the contacts, for example to the broken line position 85 of Fig. 1; and when rocked back to its normal position of Fig. 1, the inner end 64 of the core extension 63 abuts upon and is stopped upon the end of the core 53 to support and position the blow-out magnetic circuit and the arc chutes above described.

The operation of the magnetic arc extinguishing arrangement as described above involves a triple application of the reaction of current and magnetism as follows:

The contacts in the drawing are shown in Figs. 1, 5, 9, and 11 in the open position, and for purposes of description it may be assumed that when arcs are drawn between the contacts 1-4 and the contacts 2-5, the current in the arcs flows from the contact 1 to the contact 4 and from the contact 5 to the contact 2. By reason of the disposition of the parts as described, the current in these two arcs is in opposite directions and in

two adjacent parallel paths; and therefore, by the well known law, the arcs repel each other laterally.

These arcs while continuing to be mutually repelled rise in the arc chutes above described due to thermal action and the repulsion forces push them respectively in the directions toward the refractory plates 68 and 70. As the arcs rise they enter the said magnetic fields and due to the tapering density of the fields, and the density being less and less proceeding from the protuberances 66 and 67 toward the core extension 63, the reaction of the current in the arcs on these tapering fields exerts forces on them in the direction to push them both upwardly and toward the refractory side plates 71 and 72; that is to say, these forces have a component which is away from the protuberances and toward the core extension 63.

Each arc is therefore subjected to two opposite forces by magnetic action, and taking the center line of Fig. 5 as a reference line, one force, the mutually repelling force, pushes the arcs away from the center line; and the other force, the force of the tapering field, pushes the arc toward the center line, and the two forces squeeze the arc into a thin planar zone between the refractory side walls of the corresponding chutes.

These thin planar arcs also concurrently react on the magnetic fields to accelerate their upward movement and they become elongated thereby and are finally ruptured.

It has been found that the arc, squeezed into thin planar form in this manner, accompanied concurrently by the propulsion of the arc upwardly through the arc chute and across the magnetic field therein, is ruptured and goes out very quickly, and before any considerable flame is propagated; and the arc being confined to the medial portion of each arc chute is kept out of destructive contact with the refractory material of the chute.

The ease or efficiency with which the arc is extinguished in the manner above described is evidenced by the emitted sound. In the ordinary arc extinguisher in which the arc can spread out and produce flame, the sound is a ragged, tearing, explosive sound. The extinguishing of the arc by the present structure is accompanied by merely a sharp abrupt "crack" of sound.

Because the arc is extinguished so quickly and abruptly, a given amperage of current can be broken with less opening space between the contacts than by prior devices, and accordingly the magnetic circuit for operating the arm 6, and the winding 12 for energizing it, can be smaller and more economical than in prior constructions.

The principles of the contactor will function equally well with alternating current or with direct current, although in the case of alternating current some of the parts of the magnetic circuit would be laminated as is well understood by those skilled in the art.

While it is preferable to provide a magnetic core 53 energized magnetically by a winding such as 27, a permanent magnet may be employed instead, and it is believed unnecessary to illustrate or describe the same inasmuch as such a structure would result if the structure illustrated were to have a permanent magnet substituted for the core 53, and if the winding 27 were omitted.

While as shown and described, the pivoted side plates 59 and 60 and the parts assembled therewith rest in their operative positions by gravity 76 upon the engagement of the end 64 of the core

extension with the end of the core 53, there is no liability that they will be vibrated or dislodged from operative positions at the time of functioning because at that time the core extension adheres to the end of the core 53 by magnetic attraction.

Due to the proximity of the contact carrier 32 to the magnetic parts of the blowout magnetic circuit, it is preferable to make the carrier from a strip of non-magnetic material, but this is not essential to satisfactory operation.

While I have illustrated the embodiment of the invention in a detailed structure, various changes and modifications may be made in these details without departing from the principles of the invention; and the invention is comprehensive of all changes and modifications which come within the scope of the appended claims.

I claim:

1. In a contactor, contacts operable to break an electric circuit at two spaced points and disposed to draw two arcs in parallel whereby magnetic forces develop therebetween tending to move them apart; means producing two magnetic fields above the arcs respectively to rupture the arcs, comprising magnetic plate like side elements and an intermediate plate like element disposed and energized to produce said magnetic fields between the intermediate element and the side elements respectively; protuberances on the side elements projecting toward the intermediate element, disposed to cause the magnetic flux in the fields to be distributed so as to exert forces on the arcs before rupturing tending to move them in directions toward each other; the two forces on each arc, thus occurring, acting concurrently and reducing the transverse dimensions of the propeller arc therebetween before rupturing.

2. In a contactor, contacts operable to break an electric circuit at two spaced points and disposed to draw two arcs in parallel whereby magnetic forces develop therebetween tending to move them apart; means to propel the arcs upwardly to rupture them comprising members of magnetic material disposed in spaced relation transversely of the arcs to provide, when magnetically energized, two magnetic fields, one for each arc; winding means for energizing the magnetic members; protuberances of magnetic material, one for each arc, projecting respectively transversely into the fields and disposed to be energized by flux in the magnetic members, and to distribute the flux in the fields so as to exert forces on the arcs tending to move them in directions toward each other; the two forces on each arc, thus occurring, acting concurrently and reducing the transverse dimensions of the propelled arc.
